UNITED STATES PATENT OFFICE.

SIMON NEFZGER, OF LIMA, IOWA.

BICYCLE.

SPECIFICATION forming part of Letters Patent No. 623,379, dated April 18, 1899.

Application filed May 14, 1898. Serial No. 680,736. (No model.)

To all whom it may concern:

Be it known that I, SIMON NEFZGER, a citizen of the United States, residing at Lima, in the county of Fayette and State of Iowa, have 5 invented a new and useful Bicycle, of which the following is a specification.

This invention relates to bicycles and vehicles or machines of like nature mounted upon two wheels having a tandem arrangement, 10 the purpose being to so mount the pilot-wheel whereby the steering of the machine is rendered comparatively easy and may be effected without any special care on the part of the rider.

15 The invention also has for its object to combine with the stem of the steering-wheel a steadyng-bar which is at all times under the control of the rider to prevent the turning aside of the pilot-wheel in the event of its 20 striking a rock or obstruction in the path of the machine.

A further purpose of the invention is to provide a support for the steadyng-bar to prevent its inner end from bending downward 25 when subjected to pressure from above.

For a full understanding of the merits and advantages of the invention reference is to be had to the accompanying drawings and the following description.

30 The improvement is susceptible of various changes in the form, proportion, and the minor details of construction without departing from the principle or sacrificing any of the advantages thereof, and to a full disclosure of 35 the invention an adaptation thereof is shown in the accompanying drawings, in which—

Figure 1 is a side view of a bicycle constructed in accordance with and embodying the essentials of the invention. Fig. 2 is a 40 top plan view of the forward portion of the machine-frame, showing the steadyng-bar and the support or rest therefor. Fig. 3 is a detail view of the front fork. Fig. 4 is a detail section of the upper forward portion of 45 the machine-frame.

Corresponding and like parts are referred to in the following description and indicated in the views of the drawings by the same reference characters.

50 The machine-frame comprises an upper reach-bar 1, a lower reach-bar 2, the diagonal or seat-post tube 3, rear fork 4, backstays 5,

and head-tube 6, the latter occupying a relatively vertical position and having the front ends of the reach-bars 1 and 2 connected therewith. The reach-bar 1 is horizontal and straight throughout its length, whereas the reach-bar 2 has its rear portion inclined and its front portion horizontal, as shown at 7, and extending over the pilot-wheel 8. 55

The front fork 9 has its end portions curved rearwardly, so as to throw the axis of the pilot-wheel 8 in the rear of the vertical axis of the fork-stem 10, whereby the pilot-wheel drags and tends to remain parallel with the 60 line of motion of the machine, thereby obviating especial care on the part of the rider to steer the machine in a direct course. The head-tube 6 is perpendicular, and the fork-stem 10, being mounted therein, has a vertical 65 arrangement. Hence by curving the ends of the fork sides rearwardly the major part of the pilot-wheel comes in the rear of the vertical axis of the front fork, thereby resulting in keeping the steering-wheel in the line of 70 motion of the machine. 75

A steadyng-bar 11 is applied to the upper end of the fork-stem 10 and extends rearwardly within convenient reach of the rider. The rear portion of the steadyng-bar is divided or split and the separated parts are 80 spread, as shown at 12, and connected by means of a curved hand-bar 13, formed on the arc of a circle having the fork-stem 10 as an axis. A support 14, consisting of an upright bar, connects the reach-bars 1 and 2 about midway of their ends and forms a rest for the hand-bar 13, which moves thereon when steering the machine. This support 14 likewise provides means for sustaining the 85 rear end of the steadyng-bar 11 against downward pressure upon the hand-bar. 90

The steadyng-bar and its rest are adjustable vertically to accommodate their position to the convenience and comfort of the rider. 95 A post 15 is applied to or formed with the steadyng-bar and is adjustable in the fork-stem 10 and adapted to be secured therein at the located position by any of the ways common for securing hand-bars when moved up 100 or down to the required position.

The upright bar 14 is tubular, and a stem 16 is adjustable therein, being secured at the required elevation by a binding-screw 17 or

in any manner found most advantageous. An open ring or band 18 is formed with or applied to the upper end of the stem 16 and embraces the hand-bar 13, the parts being 5 disposed so that under normal conditions the hand-bar will not touch any portion of the the open ring or band, thereby permitting free movement of the hand - bar, so that the machine may be self-steering. The dis- 10 tance between the inner walls of the open ring or band and the hand-bar is comparatively slight, so that either an upward pull upon the hand-bar or a downward pressure thereon will bring it in contact with the ring 15 or band, thereby preventing straining or injury to the bar.

The seat 19 is capable of vertical adjustment and of being moved forward and rearward in the usual manner, so as to accommodate 20 its position to the rider.

The improvements are adapted to be applied to any style or make of machine, whether for ladies or gentlemen. As clearly indicated, it is preferred to have the steering-wheel of 25 less diameter than the drive-wheel, whereby the guiding, whether automatic or by design, is rendered comparatively easy.

Having thus described the invention, what is claimed as new, and desired to be secured 30 by Letters Patent, is—

1. In a bicycle or like road-machine, the combination with the front fork, a rearwardly-extending steadyng-bar having connection at its front end with the said fork, and a hand- 35 bar attached to the rear end of the steadyng-bar and formed on the arc of a circle having

the axis of the fork-stem for its center, of a rest applied to the machine-frame and having a portion encircling the hand-bar and normally out of contact therewith to admit of 40 the self-steering of the wheel and adapted to come in contact with the hand-bar and brace it on the application of upward or downward pressure upon the said hand - bar, substantially as set forth.

2. In a bicycle or like machine, the combination with the front fork, a rearwardly-extending steadyng-bar adjustable vertically with reference to the fork-stem and having direct connection therewith at its forward 50 end, and having its rear end portion spread, and a hand - bar secured to the rear terminals of the separated parts of the steadyng-bar and curved on the arc of a circle having the axis of the fork-stem for its center, of an 55 upright bar forming a part of the machine-frame and bracing it, a stem having adjustable connection with the upright bar, and a rest at the upper end of said bar consisting of an open ring or band encircling the hand- 60 bar and normally out of contact therewith and adapted to engage with and brace said hand - bar on the application of upward or downward pressure to the hand-bar, substantially as set forth.

In testimony that I claim the foregoing as my own I have hereto affixed my signature in the presence of two witnesses.

SIMON NEFZGER.
